PUMP CONTROLLING MECHANISM

William E. Hughes, Chicago, Ill., assignor to Sullivan Machinery Company, a Corporation of Massachusetts

Application January 21, 1930. Serial No. 422,429

20 Claims. (Cl. 230—4)

This invention relates to controlling mechanism for an electrically driven compressor for starting and stopping the motor automatically in accordance with the demands for air. More particularly my invention relates to controlling mechanism for a synchronous motor connected to a compressor for driving the same, to start and stop the motor when air is required or when the demand for air decreases.

One object of my invention is to provide improved controlling means for automatically stopping and starting a motor driving a compressor which is arranged to shut down the motor for a long period should the demand for pressure fluid be but small. A further object of my invention is to provide improved automatic start and stop control mechanism for a synchronous motor connected to drive a compressor. A still further object of my invention is to provide an improved control mechanism for a synchronous motor which drives a compressor and is arranged to automatically start and stop the synchronous motor in accordance with the demands for pressure fluid. A more specific object of my invention is to provide start and stop control mechanism for such a synchronous motor which need not be started and stopped in rapid succession when the demand for pressure fluid falls off. Further objects of my invention will become apparent in the course of the ensuing description and will be more particularly pointed out in the accompanying drawings.

I have disclosed for purposes of illustration one embodiment which my invention may assume in the accompanying drawings, in which

Fig. 1 is a diagrammatic view of a compressor directly connected to a synchronous motor to be driven by the latter.

Fig. 2 is a wiring diagram of controlling mechanism for stopping and starting such a synchronous motor in accordance with the principles of my invention.

In Fig. 1 there is disclosed a compound compressor having a low pressure cylinder 6 and a high pressure cylinder 7. An intercooler 8 is provided through which the fluid compressed by the low pressure cylinder 6 flows to the high pressure cylinder 7. Discharge from the compressor takes place through a conduit 9 into a receiver tank 10. A synchronous motor 11 is directly connected to the crank shaft 12 of the compressor to drive the latter. A valve 13 is arranged in the inlet 14 of the low pressure cylinder, being actuated by a spindle 15 connected to the piston 16 of a servo motor 17. When the servo motor is actuated to

bring the valve 13 to closed position, the admission of air or other fluid to the low pressure cylinder 6 is completely cut off and the compressor is thereby unloaded. Fluid for actuating the servo motor 17 is delivered thereto by means of a pipe 18 under the control of a pilot valve 19, the pilot valve being connected to the receiver tank 10 by a pipe 20. The pilot valve 19 may be set for a predetermined range of pressure within which it is desired that the compressor shall normally operate. For example, the pilot valve 19 may be set so that fluid is delivered through pipe 18 to unload the compressor when the pressure in the receiver tank reaches 100 pounds, and to vent fluid from the servo motor 17 when the pressure has dropped again to 90 pounds.

The pilot valve 19 is equipped with a solenoid 21 which moves the pilot valve mechanism into position to vent the servo motor 17 whenever the said solenoid 21 is deenergized. In other words, the compressor runs unloaded at all times when the solenoid 21 is deenergized. My improved controlling mechanism is designed to cooperate with the solenoid 21 to energize the same when the motor 11 is synchronized on the line, the solenoid 21 being deenergized whenever the motor is stopped and receiving current only when the motor has been brought up to speed and synchronized so as to be able to carry the full load of the compressor.

My improved mechanism is furthermore designed to start and stop the motor in accordance with the demands for pressure fluid. I have provided a pair of pressure switches 22 and 23. The pressure switch 22 is designed to operate within a range of 80 pounds to approximately 95 pounds in the illustrative embodiment disclosed herein in which the pilot valve 19 operates within a range of 90 pounds and 100 pounds. Pressure switch 23 closes at a pressure of 90 pounds and opens at a pressure of 100 pounds in the illustrative embodiment disclosed herein. The synchronous motor 11 is supplied with alternating current by way of three lead wires 24, 25 and 26. A main line contactor switch 27 is arranged to disconnect or connect the lines 24, 25 and 26 to the lines 28, 29 and 30 respectively which are connected to the rotating field of the motor. A solenoid 31 is connected to the actuating lever 31^a of the switch 27 so as to close the same when current flows through the solenoid 31 to actuate the same. Such current is supplied by means of a control circuit which includes the wire 32 connected to the main lead 26, a wire 33, a wire 34 and a manually operable switch 35 which may be closed to start 110

the synchronous motor if the pressure acting on pressure switch 22 be below 80 pounds. The circuit is completed through switch 22, a wire 36, wire 37, the switch 38 of timing relay 39, a wire 40, an overload relay 41, and wire 42 which is connected to the main lead wire 24. The overload relay is of a well-known type having a coil 43 inserted in the main lead line 24. The time relay 39 is of a well-known type which is designed to open the switch 38 after current flows for a predetermined length of time, for example five minutes, through its coil 44.

The pressure switch 23 is designed to control the flow of current through coil 44; and controls 15 for this purpose a circuit including a wire 45 connected to the motor terminal 30, a wire 46, a wire 47 and the holding coil 48 of a normally closed magnetic switch 49. This circuit is completed by way of a wire 50 and a wire 51 which is connected to the motor terminal 29. When no current flows through the coil 48 the magnetic switch 49 is closed and current flows by way of wires 45 and 46, the magnetic switch 49, wire 52, the coil 44, wire 53 and wire 51 to the motor terminal 29. As has been above explained, if current flows 25 through the coil 44 for a longer period than the predetermined amount (which in this embodiment is set as five minutes) the switch 38 will be opened breaking the control circuit and deenergizing the coil 31 so as to open the switch 27.

An exciter 54 is provided for supplying direct current to the field 55 of the synchronous motor 11. As shown in Fig. 2, the circuit connecting exciter 54 to the field 55 is broken at the field 36 contactor 56. When the switch 56 is closed current flows from the exciter through lines 57 and 58 to the field 55 and returns by way of wires 59, 60, the switch 56 and wire 61. The contactor 56 is opened and closed by a solenoid 62 to which 40 current is supplied by way of a wire 63 connected to the main lead wire 26. The circuit is completed through a line 64, a switch 65, wire 66, wire 34, switch 35, wires 36 and 37, switch 38, wire 40, switch 41, and wire 42 which is connected to line 24. It will thus be seen that if the 45 control circuit for the motor be broken, the solenoid 62 will at once be deenergized. It will furthermore be noted that the solenoid 62 cannot be energized until the switch 65 is closed. A differential relay 68 is provided for controlling the 50 switch 65. One side of this relay is supplied with current by wires 45, 69, 70, 34, switch 35 etc., the circuit being completed to main lead wire 24 when the main control circuit is closed. The 55 other side of the differential relay is supplied with alternating current which is induced in the field 55 as soon as the revolving field is set up in the motor 11 by closing switch 27. This current flows by way of wire 58, wire 71, switch 72, wire 60 73 to the differential relay and returns by wire 74 and wire 59 to the field 55. The frequency of 65 this induced alternating current at first is relatively high due to the motor armature being at a stand-still. However, as the armature is brought up to near its synchronous speed, due to the use of usual amortisseur windings or a usual starting motor if desired, the frequency of the induced current is reduced to a very low value as the slip-page between the armature and rotating field is 70 now small and accordingly the two sides of the differential relay are supplied with current of different frequency. As is well understood in the art, the relay 68 is then operative to close switch 65, whereupon coil 62 is energized so as to close switch 56 and open switch 72. Closure of switch

56 supplies direct current to field 55 whereupon the armature is pulled into step so that the motor operates synchronously. It is, of course, unnecessary to continue the flow of current through the differential relay 68 when the motor is once synchronized and placed across the line.

In order to coordinate the pilot valve 19 with synchronizing of the motor 11 I connect the solenoid 21 in parallel with the coil 62 by means of wires 75 and 76 connected to wires 63 and 64 respectively whereupon it will be seen that the pilot valve effects loading of the compressor when the motor is synchronized. A circuit for shortcircuiting switches 35 and 22 is provided and includes wire 77, switch 78 and wire 79 which is connected to the wire 33. The switch 78 is closed when the switch 27 is closed.

In the operation of my improved control, assuming that the equipment has been shut down and that the receiver pressure is below 80 pounds, switch 22 will have been already closed as it closes when pressure drops to or below 80 pounds. To initiate operation of the equipment the operator then manually closes switch 35 whereupon motor switch 27 is closed due to solenoid 31 being energized by current supplied from main lead 26, wires 32, 33, 34, switch 35, wires 36, 37, normally closed switch 38, wire 40, overload switch 41 (which is normally closed) and wire 42 to main lead 24. A rotating field is thus set up in the 100 synchronous motor and its armature is brought up substantially to its synchronous speed by the use of amortisseur windings in a well-known manner. When the armature is near substantially synchronous speed the differential relay mechanism 68 operates to close switch 65 thereby energizing solenoid 62 to open switch 72 and close switch 56 thus supplying the field winding 55 with direct current from exciter 54 and causing the armature to be pulled into step and up to 115 synchronous speed. With the motor being synchronously driven the compressor is now in condition to be loaded and this is effected by the energization of solenoid 21 substantially simultaneously with the energization of solenoid 62, 120 with which the solenoid 21 is connected in parallel as by wires 75 and 76. Upon energization of solenoid 21, pilot valve 19 vents pipe 18 and cylinder 17 to atmosphere thereby permitting unloading valve 13 to open and cause loading of 125 the compressor.

When the compressor has increased the receiver pressure to 95 pounds, switch 22 is opened, but the compressor continues to operate because upon closure of switch 27, switch 78 was also closed, thus causing main switch solenoid 31 to be energized by current supplied from main lead 26 through wires 32, 33, 79, switch 78, wires 77, 37, switch 38, and wires 40 and 42 connected to the main lead 24. Also, as long as the receiver pressure is at or below 90 pounds no time limit is imposed upon the compressor operation because the time element is disconnected in that switch 23 is arranged to close when receiver pressure is at or below 90 pounds, thus energizing coil 48 of magnetic switch 49 to open the otherwise normally closed magnetic switch. Receiver pressure thereby continues to build up until it reaches 100 pounds when pilot valve 19 unloads the compressor; and at the same time, or just prior thereto, switch 23 is opened by receiver pressure, thereby deenergizing coil 48 by breaking the circuit including wires 45, 46, switch 23, magnetic switch coil 48, wires 50, 51 and terminal 29, thus permitting magnetic switch 49 to close, whereupon

the time relay 39 is started by current flowing through wires 45, 46, switch 49, wire 52, coil 44, and wires 53, 51 to terminal 29. After current flows through the time relay coil 44, for say five minutes, time relay switch 38 is opened automatically, thereby deenergizing main switch coil 31 by breaking its circuit including main lead 26, wires 32, 33, 79, 77, 37, 40, etc., and thus causing main switch 27 to be opened and stop operation of the synchronous motor. If, during this five minute period, the receiver pressure drops to or below 90 pounds, pilot valve 19 operates to reload the compressor and at the same time, or just prior thereto, switch 23 is closed, thus energizing coil 48 and opening the magnetic switch 49 whereby the time relay coil 44 is deenergized and the five minute period thus prevented from becoming effective. The compressor will thus continue to operate until receiver pressure again reaches 100 pounds when the above cycle may again take place. It may happen that receiver pressure will not fall to 90 pounds within the five minute period, whereupon at the expiration of this time, switch 38 opens automatically and disconnects the control circuit so that main switch 27 opens and stops the compressor operation. Switch 38 automatically recloses, but this alone will not permit the motor to restart as switch 78 is opened along with the main switch 27. It is therefore necessary first to close switch 27 before the unit can be restarted. This restarting is controlled by switch 22 which, however, will not close until receiver pressure drops to 80 pounds. When this occurs, there is re-established the starting circuit from main lead 26 through wires 32, 33, 34, switch 35, wires 36, 37, switch 38, (which is automatically reset after being opened upon expiration of its five minute period) and wire 40 to lead 24.

When the motor circuit is broken so as to stop the compressor, solenoid 21 is deenergized, thereby positively arranging the mechanism of pilot valve 19 so that the passage for the flow of fluid from the receiver through pipe 20 to pipe 18 is maintained open and accordingly actuates servo motor 17 and unloading valve 13. This makes certain that the compressor may re-start in its unloaded condition. It is thus seen that the following series of pressure operations are performed:

1st.—The compressor when operating loaded, continues to operate until receiver pressure is built up to 100 pounds, at which time switch 23 is closed to start the time relay 39, and simultaneously therewith, or just afterwards, the compressor is unloaded by pilot valve 19 and runs idle.

2nd.—With time relay closed, the compressor idles for say, five minutes, and then stops until receiver pressure drops to 80 pounds when switch 22 closes and the compressor pumps up to 100 pounds.

3rd.—However, if receiver pressure drops to or below 90 pounds before expiration of the five minute period, the pilot valve loads the compressor and the time relay is disconnected by closure of switch 23, whereupon receiver pressure is again built up to 100 pounds.

It will of course be understood that the various pressure limits herein described may be varied in accordance with desired operating conditions, and it will also be understood that the upper pressure limit for the time relay switch 23 may be slightly less than the unloading limit of the pilot valve 19, thereby insuring that the time period will be started when the receiver pressure has reached its upper limit. Otherwise, if the adjustment of the upper limit of the time switch 23 should be slightly above that of the unloading limit, the time switch could never be placed in operation, as the compressor would be unloaded before it had pumped pressure sufficiently high to operate the time limit switch. It is therefore essential that the time period be started slightly before, and in any event, not later than when the compressor is unloaded. It is desirable also that the compressor should not be loaded when the time limit switch stops operation of the compressor, which would be the case if the lower or loading limit of the pilot valve 19 was higher than the pressure at which the pressure switch 23 is closed to terminate running of the time interval of switch 38. For example, assume the compressor to load at 91 pounds and the running of the time limit to be interrupted only if the pressure drops to 90 pounds. The withdrawal of air or other fluid from the receiver tank 10 may be at so slow a rate that the 5 minute time interval elapses before the pressure in the receiver tank 10 drops to 91 pounds. In this case, the motor 11 is shut down (by opening of switch 38) with the compressor unloaded. But the withdrawal of fluid from the receiver tank 10 may be fast enough to lower the pressure therein to 91 pounds before the 5 minute time interval elapses. The compressor now resumes pumping of fluid into the receiver tank 10. The running of the time period of switch 38 cannot be interrupted, however, unless the pressure drops still lower (to 90 pounds); and the compressor might therefore be stopped (by opening of switch 38 and the ensuing interruption of the current supply to the motor 11) in loaded condition. While disconnection of the power supply to the synchronized motor unloads the compressor through the deenergization of solenoid 21, yet this operation may not be in exact coordination, whereby the compressor might be stopped during compressing operations. However, by having the coil 44 of the time limit switch disconnected by opening of pressure switch 23 at a pressure slightly above the unloading limit this difficulty will be avoided. It is desired to rely upon the de-energization of solenoid 21 to unload the compressor, the low limit of the time relay can be set at a pressure below the loading limit of the pilot valve. In this case, the pressure is pumped to 100 pounds, the pilot valve then unloads the compressor, the motor is stopped after a predetermined time interval (which may be made much shorter than five minutes if desired), and pumping is resumed when the receiver pressure falls to 80 pounds.

If such precise adjustment of the pressure switch 23 were possible that its operation would coincide exactly with the operation of the pilot valve 19, in other words if the pressure switch 23 could be set to open at precisely the same pressure which causes functioning of the pilot valve 19 and to close at precisely the same pressure which causes the pilot valve 19 to vent, the slight differences in pressure limits for operating the time element would not have to be employed. It will, therefore, be understood that where reference is made to having the pressure limits for the time element the same as the pressure limits for the unloading pilot valve, variations may or may not be employed in accordance with the above description. It is also seen that magnetic switch 48, 49 may be eliminated if switch 23 is designed to close at 100 pounds or slightly less and open at 90 pounds or somewhat above, in which case wire 135

47 is connected directly to coil 44, the operation otherwise being as previously described.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a compressor system having a prime mover operated compressor provided with unloading mechanism and connected to supply pressure fluid to a receiver, the combination comprising a pilot valve constructed and arranged to effect loading and unloading of said compressor at predetermined limits of pressure in said receiver, means whereby when the compressor is unloaded it will idle for a limited period of time and then be stopped, and means whereby if the receiver pressure drops substantially to the loading limit of said pilot valve before said time period expires the compressor is reloaded and will build up receiver pressure until the pilot valve unloads the compressor.

2. Apparatus for controlling a prime mover operated compressor having load controlling mechanism and connected to supply pressure fluid to a receiver comprising, in combination, means for loading and unloading said compressor at predetermined limits of pressure in the receiver, means constructed and arranged, when rendered operative upon occurrence of a predetermined receiver pressure, to determine a limited period of time and to stop operation of the compressor when said time period expires independently of further pressure control of the time determining means, and means for initiating operation of said time determining means when receiver pressure reaches a predetermined maximum value.

3. Apparatus for controlling a prime mover operated compressor having load controlling means comprising, in combination, means for loading and unloading said compressor at predetermined limits of discharge pressure from said compressor, time control means rendered operative at a predetermined pressure limit and rendered inoperative at another predetermined limit, and means for controlling said time control means so as to render the same operative and arranged to permit said time control means to stop operation of the compressor upon expiration of the predetermined time period even though the compressor discharge pressure remains between the pressure limits at which said time control means is rendered operative or inoperative.

4. Apparatus for controlling a prime mover operated compressor comprising, in combination, a pilot valve constructed and arranged to control the loading and unloading of said compressor at predetermined lower and upper pressure limits respectively, and separately compressor discharge pressure controlled means whereby when the compressor is unloaded at said upper pressure limit the compressor is adapted to idle for a predetermined period of time and then automatically be stopped even while the upper pressure limit is maintained substantially.

5. Apparatus for controlling a prime mover operated compressor having load controlling mechanism comprising, in combination, means for loading and unloading the compressor at lower and upper pressure limits respectively, time

controlling means arranged to stop compressor operation when the compressor idles for a predetermined length of time between substantially its loading and unloading limits, and means whereby said time controlling means is constructed and arranged to stop the compressor operation at the end of the same predetermined time irrespective of variations in the compressor discharge pressure between said loading and unloading limits.

6. Apparatus for controlling a prime mover operated compressor comprising, in combination, a pilot valve constructed and arranged to control the loading and unloading of said compressor at predetermined pressure limits, time control mechanism arranged to stop compressor operation when the compressor idles unloaded for a predetermined time period, a main switch for controlling said prime mover, a plurality of circuits for controlling said switch and each including said time control mechanism, means whereby one of said main circuits is opened when compressor discharge pressure reaches a predetermined value, and means for opening the other of said circuits upon occurrence of a predetermined higher pressure limit.

7. Apparatus for controlling a prime mover operated compressor comprising, in combination, a pilot valve constructed and arranged to control the loading and unloading of said compressor at predetermined pressure limits, time control mechanism arranged to stop compressor operation when the compressor idles unloaded for a predetermined time period, a main switch for controlling said prime mover, a plurality of main control circuits for controlling said switch and each including said time control mechanism, means whereby one of said control circuits is opened when pressure discharge pressure reaches a predetermined value, and means for opening the other of said circuits including a circuit arranged upon occurrence of a predetermined higher pressure limit to initiate operation of said time control mechanism whereby the second one of said main control circuits is controlled in accordance with a given time period.

8. Apparatus for controlling a prime mover operated compressor comprising, in combination, a solenoid operated controlling means for said prime mover whereby the prime mover may be started and stopped, time control means for determining a period of time during which said compressor may run idle, main control circuits for said solenoid and each of which includes said time control means, means for opening one of said control circuits when a predetermined compressor discharge pressure obtains, and means for initiating operation of said time control means upon occurrence of a predetermined higher discharge pressure whereby upon expiration of said time period the second one of said main control circuits automatically effects opening of the solenoid controlled means to stop operation of the prime mover and compressor.

9. The combination set forth in claim 8 further characterized in that said means for opening the first of said main control circuits is reclosed before the occurrence of a predetermined minimum pressure.

10. The combination set forth in claim 8 further characterized in that the means for controlling the first of said main control circuits is arranged to reclose the same upon occurrence of a predetermined minimum pressure thereby to initiate operation of the prime mover and to

- close automatically the second one of said main control circuits.
11. Apparatus for controlling a synchronous motor driven compressor comprising, in combination, means for unloading the compressor, and means for making and breaking the circuit supplying current to the synchronous motor including a relay device whereby the breaking of the circuit is normally prevented until the end of a predetermined time interval after unloading of the compressor by said unloading means. 80
12. In a compressor system, in combination, a compressor, unloading means therefor, a driving motor for said compressor, a control switch for said driving motor, and controlling means operative on the attainment of a predetermined compressor discharge pressure to cause said unloading means to unload the compressor and to thereafter cause opening of said switch or not in accordance with the time the compressor operates unloaded including separate compressor discharge pressure responsive devices respectively controlling the unloading means and the switch. 85
13. In a compressor system, in combination, a compressor, unloading means therefor, a driving motor for said compressor, a control switch for said driving motor, and controlling means operative on the attainment of a predetermined compressor discharge pressure to cause said unloading means to unload the compressor and to thereafter cause opening of said switch or not in accordance with the time the compressor operates unloaded including a circuit established substantially simultaneously with unloading and controlling opening of said switch. 90
14. In a compressor system, in combination, a compressor, unloading means therefor, a driving motor for said compressor, a control switch for said driving motor, and controlling means operative on the attainment of a predetermined compressor discharge pressure to cause said unloading means to unload the compressor and to thereafter cause opening of said switch or not in accordance with the time the compressor operates unloaded including separate compressor discharge pressure responsive devices controlling the unloading means and the switch, said compressor discharge pressure responsive device controlling the unloading means having associated therewith means precluding loading except when the driving motor is operating at substantially full speed. 100
15. In a compressor system, in combination, a compressor, unloading means therefor, a driving motor for said compressor, a control switch for said driving motor, and controlling means operative on the attainment of a predetermined compressor discharge pressure to cause said unloading means to unload the compressor and to thereafter cause opening of said switch or not in accordance with the time the compressor operates unloaded including a time delay relay controlling running of the motor and operative to interrupt the same when energized for a predetermined time, said controlling means including means for precluding restarting of said motor, if the same be stopped as aforesaid, until after compressor discharge pressure drops materially below the normal reloading value. 105
16. In a compressor system, in combination, a compressor, unloading means therefor, a driving motor for said compressor, and controlling means automatically operative to start said compressor when discharge pressure reaches a predetermined minimum, to load the compressor when motor speed reaches a predetermined minimum, to unload the compressor when compressor discharge pressure reaches a predetermined maximum, and to stop said motor if the compressor operates unloaded for a predetermined time including means for preventing stopping the motor if a predetermined drop in compressor discharge pressure precedes the expiration of said predetermined time. 110
17. In a compressor system, in combination, a compressor, unloading means therefor, a driving motor for said compressor, a control device controlling driving of said compressor by said driving motor, controlling means for said unloading means operative during continued driving of said compressor to load the compressor at a predetermined minimum discharge pressure and to unload it at a predetermined maximum discharge pressure, and controlling means for said control device arranged to operate the same automatically to interrupt compressor drive if the compressor operates unloaded for a predetermined time and including means for precluding operation of said device to reinitiate compressor drive after the automatic interruption thereof until compressor discharge pressure falls substantially below the predetermined minimum aforesaid. 115
18. Apparatus for controlling a prime mover operated compressor comprising compressor unloading means having controlling means operative upon occurrence of a predetermined condition of operation to cause said unloading means to unload the compressor, and means for stopping the compressor after the same operates under substantially said predetermined condition for a given time period including compressor drive interrupting means and controlling means therefor responsive independently of said first mentioned controlling means to a condition of operation of said compressor. 120
19. Apparatus for controlling a synchronous motor driven compressor comprising, in combination, means responsive to compressor discharge pressure variations for unloading the compressor, means for making and breaking a circuit supplying current to the synchronous motor including a relay device whereby the breaking of the circuit is normally prevented until the end of a predetermined time interval after unloading of the compressor by the unloading means, and common means for controlling both said unloading means and said circuit making and breaking means. 125
20. Apparatus for controlling a synchronous motor driven compressor comprising, in combination, means, responsive to compressor discharge pressure variations for unloading the compressor, means for making and breaking a circuit supplying current to the synchronous motor including a relay device whereby the breaking of the circuit is normally prevented until the end of a predetermined time interval after unloading of the compressor by the unloading means, and common fluid pressure responsive means for controlling both said unloading means and said circuit making and breaking means. 130
21. In a compressor system, in combination, a compressor, unloading means therefor, a driving motor for said compressor, and controlling means responsive to compressor discharge pressure variations for unloading the compressor, means for making and breaking a circuit supplying current to the synchronous motor including a relay device whereby the breaking of the circuit is normally prevented until the end of a predetermined time interval after unloading of the compressor by the unloading means, and common fluid pressure responsive means for controlling both said unloading means and said circuit making and breaking means. 135
22. In a compressor system, in combination, a compressor, unloading means therefor, a driving motor for said compressor, and controlling means responsive to compressor discharge pressure variations for unloading the compressor, means for making and breaking a circuit supplying current to the synchronous motor including a relay device whereby the breaking of the circuit is normally prevented until the end of a predetermined time interval after unloading of the compressor by the unloading means, and common fluid pressure responsive means for controlling both said unloading means and said circuit making and breaking means. 140
23. In a compressor system, in combination, a compressor, unloading means therefor, a driving motor for said compressor, and controlling means responsive to compressor discharge pressure variations for unloading the compressor, means for making and breaking a circuit supplying current to the synchronous motor including a relay device whereby the breaking of the circuit is normally prevented until the end of a predetermined time interval after unloading of the compressor by the unloading means, and common fluid pressure responsive means for controlling both said unloading means and said circuit making and breaking means. 145

WILLIAM E. HUGHES.

CERTIFICATE OF CORRECTION.

Patent No. 1,920,985.

August 8, 1933.

WILLIAM E. HUGHES.

It is hereby certified that error appears in the printed specification of the above numbered patent requiring correction as follows: Page 1, line 95, for "90" read 90+; and line 96, for "100" read 100--; and page 5, line 134, claim 20, strike out the comma after "means"; and that the said Letters Patent should be read with these corrections therein that the same may conform to the record of the case in the Patent Office.

Signed and sealed this 13th day of November, A. D. 1934.

Leslie Frazer
